SLIDE PROJECTOR

Theodore S. Briskin, Chicago, Ill., John E. Davis, Sherman Oaks, Calif., and Robert L. Moore, La Grange Highlands, Ill., assignors to Revere Camera Company, Chicago, Ill., a corporation of Delaware

Application October 14, 1955, Serial No. 38,361

Term of patent 14 years

(Cl. D61—1)

FIG. 1

Des. 180,577

PAGE 2

FIG. 2

FIG. 3

FIG. 4

Fig. 1 is a front elevational view of a slide projector showing our new design;

Fig. 2 is a top plan view thereof;

Fig. 3 is a side elevational view thereof; and

Fig. 4 is a side elevational view thereof, showing the side opposite to that shown in Fig. 3.

We claim:

The ornamental design for a slide projector, substantially as shown.
